G. W. PACKER

SCRAPER

Filed Nov. 2, 1922

UNITED STATES PATENT OFFICE.

GLENN W. PACKER, OF CHICAGO, ILLINOIS, ASSIGNOR TO GOODMAN MANUFACTURING COMPANY, OF CHICAGO, ILLINOIS, A CORPORATION OF ILLINOIS.

SCRAPER.

Application filed November 2, 1922. Serial No. 598,480.

To all whom it may concern:

Be it known that I, GLENN W. PACKER, a citizen of the United States, residing at Chicago, in the county of Cook and State 5 of Illinois, have invented certain Improvements in Scrapers, of which the following is a specification.

This invention relates to an improvement in scrapers, and more particularly to the type 10 of reciprocable scrapers disclosed in my prior application, bearing Serial Number 470,771, filed May 19, 1921, in which the scraper is provided with a pair of lateral opening hinged wall portions at its rear 15 end, said wall portions being operatively connected with a head rope and a tail rope so that they may be opened when the scraper is pulled rearwardly into a pile of loose material, and closed when the scraper is pulled 20 in the opposite direction, so as to inclose a load of material in the scraper. In the construction of a scraper above described, the head and tail ropes have divided terminals, each side of which are operatively connected 25 with only one of the hinged portions. Under certain operating conditions, however, it is found desirable to exert a pull on one of the ropes, as for instance, the head rope, at an angle to the normal longitudinal axis of the 30 scraper, and when this is done, one of the hinged portions has a tendency to open, owing to the unequal tension on the two terminals of the head rope.

The principal object of the present invention is to provide an improvement in the construction of actuating mechanism for the hinged wall portions of a scraper of the open end type, above described, whereby a pull may be exerted on the head and tail 40 ropes at various angles with respect to the longitudinal axis of the scraper, which pull is operative to actuate both hinged portions under substantially equal tensions.

My invention may be understood by referring to the accompanying drawings, in which Figure 1 is a plan view of the scraper, embodying one form of my invention. Figure 2 is a view in vertical cross section of scraper shown in Figure 1. Figure 3 is an

enlarged sectional view taken on line 3, 3 50 of Figure 1.

In the embodiment shown in the drawings, the scraper is adapted to be moved by flexible draft ropes comprising a head rope 10 and a tail rope 11 for moving the scraper 55 forwardly and rearwardly, respectively. The apparatus may be set up in any ordinary manner with the guide ropes running over fixed guides or sheaves and operatively connected with any suitable power device, 60 such as a hoisting engine.

The scraper comprises a body portion 12, having side walls 13, 13, connected by front and rear cross members 14 and 15, respectively. The drawings illustrate a preferred 65 form of scraper having no bottom, but a bottom may be found desirable under some circumstances, and may be provided without departing from the scope of my invention. The bottom margins of the walls 13, 13 are inclined to turn inwardly to form substantially horizontal cutting edges, 16, 16. The rear end of the scraper comprises two upright wall portions or doors 17, 17, pivotally connected to the rear end of the side 70 walls, as indicated at 18. The arrangement is such that the doors normally form a closure for the rear end of the scraper, but are mounted to swing laterally and rearwardly into a position substantially in alignment with the adjacent side walls of the 75 scraper. The bottom margins of the doors 17, 17 are preferably inclined or turned inwardly to form cutting edges 19, 19 similar to the cutting edges 16, 16 of the side walls. 80

Means coacting with the draft ropes are provided for actuating the rear wall portions, so as to open the rear end of the scraper when it is being moved rearwardly and close the rear end while it is being 85 moved forwardly. This is accomplished by operatively connecting both the head rope 10 and the tail rope 11 to the doors 17, 17, so as to tend to move them in opposite directions, depending upon the relative tension 90 on the two draft devices. In the embodiment illustrated, head rope 10 is connected 95 at the forward end of the scraper to a flexible

member 20. This flexible member is preferably a continuous member having two front end portions 21, 21 connected to the head rope by suitable means, such as clamp 22, and each extending laterally toward one side of the scraper to pass about a guide member or sheave 23, mounted adjacent the forward edge of a wall portion 13. From thence the flexible member passes rearwardly about a guide or sheave 24, mounted on the adjacent door 17, and thence forwardly again about a sheave 25 mounted centrally of a cross brace 26 which extends between and connects the wall portions 13, 18. From thence the flexible member extends rearwardly about a second member 24 on the other door 17, and forwardly about a guide 23 mounted similarly to the guide already described as being adjacent the front end of the opposite wall. It will thus be seen that the flexible member 20 runs freely about the various sheaves with which it is engaged, so that the head rope 10 may be pulled at various angles with respect to the longitudinal axis of the scraper, but at all angles exerts a substantially uniform tension on both sheaves 24, 24 mounted on the doors, as described.

Referring now to the tail rope connections, it will be seen that said rope extends between the ends of the doors 17, 17 and is provided at its end with a sheave or guide 30, mounted in a block 31. A flexible member 32 is turned rearwardly about the sheave 30 and from thence forwardly toward each side about sheaves 35, 35, and from thence rearwardly to clamps 34, 34, mounted on opposite sides of the scraper. Each of the sheaves 35, 35 are mounted on a movable cross bar 36. In the figures, this cross bar is located immediately under the cross brace 26, as shown in Figure 1. It is mounted to slide transversely between the guide members 41, 41, mounted on opposite walls of the scraper. The movable bar 36 is connected with each of the doors 17, 17, by means of a pair of links 45, 45 which are each pivotally connected at 47 to a forwardly projecting member 48, mounted on its respective door. The forward end of each link, 45, is pivotally connected to the movable bar 36 by suitable means such as a pin 44. In the construction shown the front ends of the link 45, 45 extend underneath the sheaves 35 and their terminal ends 46, 46 are turned upwardly to retain the flexible member 32 on the sheaves.

By means of the connecting links 45, 45, the doors 17, 17 are swung outwardly when the movable crossbar 36 is moved rearwardly by operation of the tail rope 11, which acts through the flexible member 32 for this purpose. The movement of the cross bar 36 is limited in its forward position by stops 50, 50, in which position the doors

17, 17 are fully closed, and are limited also in its rearmost position by suitable means, such as stops 51, 51, formed by the upright portions of the cross member 15, which extend downwardly into a position across the guiding members 41, 41, as shown in Figures 2 and 3. In the rearmost position of the cross bar 36 the doors 17, 17 are in their fully open position as shown in dotted lines in Figure 1.

From the above it will be seen that a scraper constructed as described may be reciprocably operated so that the rear doors 17, 17 are opened laterally by the tail rope into substantially parallel relation with each other, and offer a minimum resistance as the scraper cuts into the material to be gathered. The tension on the tail rope is exerted in substantially equal proportions to both doors, owing to the arrangement of the flexible member 32, even though the draft on the tail rope is not directly on the longitudinal axis of the scraper, and the doors 17, 17 will be operated simultaneously owing to their common connection with the movable cross bar 36. When the scraper has advanced sufficiently to gather a load, the pull on the tail rope is discontinued and tension is placed on the head rope 10. Owing to the continuous arrangement of the flexible member 20, the head rope may also be pulled at various angles with respect to the scraper, and a substantial equal tension on both hinged members 17, 17 will be exerted to close the same. Said hinged members will be closed simultaneously as in the case of the operation of the tail rope, owing to their common connection to the movable cross bar 36.

Although I have shown and described one form in which my invention may be embodied, it will be understood that many other means may be employed for accomplishing the same results, without departing from the spirit and scope of my invention. I do not, therefore wish to be understood as limiting myself to the specific construction illustrated herein excepting as specifically limited in the appended claims.

I claim as my invention:

1. A scraper having side walls, two end portions each pivotally connected with one of said walls to swing laterally, guide devices on said end portions, and draft means for reciprocably moving said scraper including a continuous draft member trained about both of said guide devices and cooperating with other guide devices on said scraper to afford substantially equal tensions to both of said end portions tending to actuate the same.

2. A scraper having side walls, two end portions each pivotally connected with one of said walls to swing laterally, guide devices on said end portions, draft means for reciprocably moving said scraper including a

continuous draft member trained about both of said guide devices and cooperating with other guide devices on said scraper to afford substantially equal tensions to both of said 5 end portions tending to actuate the same, and means operatively connecting said end portion to positively actuate them simultaneously.

3. A scraper having side walls, two end 10 portions each pivotally connected with one

of said walls to swing laterally, draft means for reciprocably moving said scraper, means coacting with said draft means for actuating said end portions, and means operatively connecting said end portions together to actuate them simultaneously. 15

Signed at Chicago, in the county of Cook and State of Illinois, this 30th day of October, 1922.

GLENN W. PACKER.
